CLAIM

The ornamental design for a water timer, as shown and described.

DESCRIPTION

FIG. 1 is a front elevation view of a water timer showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and

FIG. 8 is another perspective view thereof; and,

FIG. 9 is an enlarged detail of the encircled portion 9 in FIG. 3.

The dash-dot-dash lines in FIG. 3 and FIG. 9 show the bounds of the detail and form no part of the claimed design. The dash-dash lines show portions of the water timer that form no part of the claimed design.
